METHOD OF FILLING AN ABSORBER-
GENERATOR

Ernst Noebel, Berlin, Germany, assignor to Siemens-Schuckertwerke Aktiengesellschaft, Berlin-Siemensstadt, Germany, a corporation of Germany

Application December 10, 1932, Serial No. 646,737
In Germany December 14, 1931

4 Claims. (Cl. 62—179)

My invention relates to a method of filling an absorber-generator ready to be built in an absorption refrigerating apparatus operating with solid absorbents.

5 According to the invention the absorbent is applied in a finely distributed form to metallic wool or cuttings or any other suitable heat conductor; whereupon the absorber-generator is charged with the metallic wool thus treated and
10 then the absorbent saturated, for instance, with ammonia after closure of the absorber-generator. On saturating the treated metallic wool, the absorbent applied to the latter swells and fills up the entire space for the reception of the solid ab-
15 sorbent in the absorber-generator. According to the method of my invention the absorber-generator need not necessarily be provided inside with special heat conducting walls, since the heat con-
duction in the metallic wool is sufficient to sup-
20 ply heat to the solid absorbents and to carry off the heat of absorption. The preparation of the absorber-generator is thus greatly simplified and by far more economical. In order to apply the absorbent, for instance, strontium bromide, not
25 yet enriched with the operating medium to a good heat conductor, metallic wool or similar substances may, for instance, be immersed into the liquefied absorbent, or the liquefied absorbent may be sprayed on the metallic wool. In
30 both cases the metallic wool is coated with a thin vitreous layer of the absorbing medium.

In the accompanying drawing is illustrated an embodiment of my invention.

As shown in the drawing, the absorber-generator consists of a cylindrical jacket 1 and a concentric inner jacket 2 which are combined to a completely closed vessel by welding cambered end covers 3 and 4 thereto. The inner jacket 2 serves for the reception of the heating element which
35 produces the heat during the generating period. The cover 4 is provided with a branch 5 to which a gas conduit is connected leading to the condenser (not shown). 6 denotes a thermometer pocket projecting into the interior of the ab-
40 sorber-generator.

The preparation of such an absorber-generator ready to be built in an absorption refrigerating apparatus is carried out as follows. At first the outer jacket 1 and the inner jacket 2 are com-
50 bined by welding the cover 3 thereto. At the open end of the vessel thus formed metallic wool
7 coated with pure absorbing medium in the above-described manner is charged in said ves-
sel, care being taken to uniformly fill the con-
55 tainer with the filling medium by ramming the

charge to such an extent as to permit the absorb-
ent, owing to the subsequent saturation with the
operating medium, to swell up in the desired man-
ner, so that a compact, finely porous and good
heat conducting mass results, which firmly con-
tacts with the walls of the absorber-generator.
After the vessel has been completely charged
the cover 4 is welded thereto; whereupon the ab-
sorbing medium is saturated with the operating
medium. In such an absorber-generator, the
metallic wool serves chiefly to conduct the heat
to the walls thereof. Since the filling material
is highly porous, the vaporous operating medium
may be easily supplied to or discharged from all
points of the absorber-generator. No special heat
conducting walls being necessary inside the space
of the absorber-generator, the latter is conse-
quently utilized to a higher degree.

The metallic wool is introduced into the ab-
sorber-generator at a temperature of about 300
to 400 centigrade immediately after the immer-
sion into the liquefied absorbing medium or aft-
er spraying the liquefied absorbing medium in a
heated state on the metallic wool. In this man-
ner, the absorbing medium is prevented to a great
extent from taking up moisture so that a reliable
operation of the refrigerating apparatus is en-
sured, since slight traces of moisture in the solid
absorbent may give rise to serious troubles. In
the method hitherto employed, it was necessary
to heat the boiler after charging it with the
absorbing medium so as to remove the residual
moisture from the absorbing medium. This meas-
ure is dispensed with in the novel absorber-gen-
erator so that a further economy is obtained by
the method according to the invention.

I claim as my invention:—

1. A method of preparing a filling mass for the generator-absorber of an absorption apparatus in which a solid absorbent capable of be-
ing swelled is utilized, consisting in immersing a good heat conducting material in the liquefied
absorbing medium so as to provide the heat con-
ducting material with a coat of said absorbing
substance.

2. A method of preparing a filling mass for the generator-absorber of an absorption apparatus in which a solid absorbent capable of being swelled is utilized, consisting in immersing metallic wool in the liquefied absorbing medium so as to pro-
vide the metallic wool with a coat of said ab-
sorbing substance.

3. A filling material for generator-absorbers of absorption apparatus in which a solid absorbent capable of being swelled is utilized consisting of

compressible metallic heat conducting material uniformly coated with a solid absorbent.
4. A method of preparing a generator-absorber for an absorption apparatus in which a solid absorbent capable of being swelled is utilized, comprising the steps of immersing a good heat conducting material in the liquefied absorbing me-

dium so as to provide the heat conducting material with a coat of said absorbing medium, charging the generator-absorber with the heat conducting material thus prepared, closing the generator-absorber and saturating the absorbing medium with the operating medium. 80
